UNITED STATES PATENT OFFICE.

WILLIAM C. FISHER, OF BOSTON, MASSACHUSETTS, ASSIGNOR OF ONE-HALF
TO CHARLES E. AND FRANK FULLER, OF SAME PLACE.

CIRCUIT-CLOSER FOR BURGLAR-ALARMS.

SPECIFICATION forming part of Letters Patent No. 279,483, dated June 12, 1883.

Application filed December 27, 1882. (No model.)

To all whom it may concern:

Be it known that I, WILLIAM C. FISHER, of Boston, county of Suffolk, State of Massachusetts, have invented an Improvement in Circuit-Closers for Burglar-Alarms, of which the following description, in connection with the accompanying drawings, is a specification, like letters on the drawings representing like parts.

10 My invention relates to a circuit-closer for burglar-alarms, it being intended to be mounted in a window-frame and operated by the movement of the sashes to close an electric circuit, and thus sound an alarm when the sashes are moved.

15 The apparatus consists, essentially, of a frame-plate mounted horizontally in the window-frame and occupying a portion of the guides for both sashes, it being preferably located at the point where the meeting-rails of the sashes remain when the window is wholly closed. The said plate is provided with two movable keys, having projections that are engaged by the sashes when moved to open the 20 window, thus pressing the said keys into contact with a co-operating yielding contact point or spring mounted on the said frame-plate, but insulated therefrom, the said spring forming one terminal, and the frame-plate, with its 25 keys, forming the other terminal of the circuit to be closed. By mounting the apparatus horizontally its construction is simplified, and the space occupied by it, and consequently the amount of wood that has to be cut away from 30 the window-frame to receive it, is reduced.

35 Figure 1 is a horizontal section of a portion of a window frame and sashes provided with a circuit-closer embodying this invention; and Figs. 2 and 3, front and rear elevations, respectively, of the circuit-closer detached.

40 The circuit-closer consists, essentially, of a metal plate, *a*, provided on its rear side with lugs *b*, between which are mounted the movable keys *c c'*, provided with projections *c'*, extending through openings 2 in the plate *a* beyond the front face thereof, as shown in Fig. 1. The said keys are in this instance shown as pivoted upon spindles *d*, mounted in the lugs *b* of the frame-plate, and are acted upon 45 by springs *e*, tending to keep the projections *c'*

of the keys *c c'* forced out through the openings 2 in the plate *a*, as shown in Fig. 1, but yielding to permit the said keys to be turned back on their pivots, as shown in dotted lines at the right of Fig. 1, when the sash is moved so as 55 to bear against the projecting end of the key.

The keys *c c'* are shown as in metallic connection with the plate *a*, and form one terminal of the circuit to be closed, the other terminal being connected with the co-operating contact-spring *f*, mounted on a block, *h*, of insulating material received between the lugs *b* and secured to the plate *a*, as by screw *i*. The lugs *b*, which in this instance serve to hold the pivot-spindles *d* of the movable keys, are intended specially to receive and hold rigidly between them the block *h*, of insulating material, on which the contact-point *f*, co-operating with the said keys, is mounted, the said lugs, together with the plate *a*, forming a rigid 70 and sufficient frame-work for maintaining the co-operating parts of the circuit-closer in the proper relative position.

In operation the apparatus is connected with the frame of the window, as shown in Fig. 1, it being cut away to receive lugs *b* and afford space for the movement of the key *c* at the rear of plate *a*, which is flush with the frame and connected therewith by screws in the usual manner, it being preferably located at the 75 point occupied by the meeting-rails *m n* of the sashes when the window is closed. The sashes are cut away or recessed, as shown at 3, to permit the keys *c c'* to remain in their normal position when the window is closed, and the 80 said recess 3 may be extended any desired distance up or down the sash to permit it to be open a certain distance without operating the circuit-closer. When, however, the sash is moved so that the recessed portion is carried 85 beyond the projection of the key *c* or *c'*, the unrecessed portion of the sash, acting on the said projection, forces the key back, as shown in dotted lines, Fig. 1, making the connection between the said key and the spring *f*. It 90 will be seen that the movement of either key closes the same circuit, and a very simple compact apparatus is afforded for indicating the movements of both sashes.

The invention is not limited to the exact 100

construction of the circuit-closer herein shown, the essential feature of which consists in mounting the keys in a plate transversely to the window-frame, thus forming a compact device for operation with both sashes.

5 I claim—

1. The herein-described circuit-closer for burglar-alarms, consisting of the flat frame-plate adapted to be mounted in a window-frame transversely to the sash-guides, and provided with openings near its ends, one in each sash-guide, combined with the independently-movable keys having projections extending through the said openings and co-operating contact-points normally insulated from the said keys, substantially as and for the purpose described.

2. The frame-plate provided with lugs on its rear face and with openings near its ends, combined with independently-movable keys having projections extending through the said openings, and the insulating-block and contact-spring received between the said lugs and held by them in proper position to co-operate with the said movable keys, substantially as 25 described.

In testimony whereof I have signed my name to this specification in the presence of two subscribing witnesses.

WM. C. FISHER.
